JOHN B. STONER, OF NEW YORK, N. Y., ASSIGNOR TO HIMSELF, L. MENDELSON, AND T. CROMMELIN, OF SAME PLACE.

Letters Patent No. 74,169, dated February 4, 1868.

IMPROVEMENT IN BALLASTING VESSELS.

The Schedule referred to in these Letters Patent and making part of the same.

TO ALL WHOM IT MAY CONCERN:

Be it known that I, JOHN B. STONER, of the city, county, and State of New York, have invented a new and useful Improvement in Ballasting Vessels; and I do hereby declare that the following is a full, clear, and exact description thereof, which will enable others skilled in the art to make and use the same, reference being had to the accompanying drawings, forming part of this specification, in which—

Figure 1 is a vertical longitudinal section of a vessel, illustrating several modes of carrying my invention into practical use, taken through the line *x x*, fig. 2.

Figure 2 is a detail cross-section of the same, taken through the line *y y*, fig. 1.

Figure 3 is a detail sectional view, taken through the line *z z*, fig. 1.

Similar letters of reference indicate corresponding parts.

My invention has for its object to furnish an improved mode of temporarily ballasting a vessel when necessary, by lowering weights into the water, so as to prevent the rolling or capsizing of said vessel; and it consists in temporarily ballasting the vessel, by a weight or weights pivoted to, or otherwise connected with, the hull of said vessel, in such a manner that they may be quickly and conveniently lowered into the water when required, and readily raised again when not required.

A represents the hull of a vessel. B is a weight, made of a size and weight varying with the size and form of the vessel to which it is attached. C are rods rigidly and securely attached to the weight B, and extending back with a curve corresponding with the form of the vessel. The ends of the rods C are pivoted to the middle of the upper part of the vessel's hull by bolts, or other convenient means, so that the weight B may be raised and lowered freely. D is a rope or chain, the end of which is securely attached to the weight B, which passes up over a pulley or pulleys E, attached to the upper part of the bow of the vessel, and thence back to some convenient place, where its free end is secured to a belaying-cleat, belaying-pin, or in some other convenient manner. F is a weight, which may be lowered and raised vertically, and the lower part of which is so formed that when raised into and secured in the recess G, formed for its reception, its lower outside surface may conform to and coincide with the form of the vessel's bottom, so as when raised to offer no obstruction to the vessel's movement through the water. The recess G, for the reception of the weight F, is formed of metal or other suitable material, set and secured in a hole cut through the bottom of the vessel, the part of the vessel weakened by cutting said hole being strengthened by metallic flanges or plates, H, formed upon or firmly attached to said metallic recess, and securely bolted to the vessel's bottom, as shown in figs. 1 and 2. From the top plate of the recess G to the deck, or some other convenient part of the vessel, extends a well or oblong tube, S, having pipes or tubes formed in its narrower sides, said tubes being slotted upon their inner sides, from their upper ends nearly to their lower ends. To the upper side of the weight F are securely attached the lower ends of two rods, I, the upper ends of which are connected by a short cross-bar, J, which moves up and down as the weight F is being raised or lowered through the slotted sides of the tubes in the well S. The upper ends of the rods I, just below the cross-bar J, are enlarged, or made cone-shaped, to fit into the contracted or conical-shaped lower parts of the tubes in the well S, through which the said rods I move up and down. To the central part of the cross-bar J is attached a rope or chain, K, which passes over a pulley attached to some suitable support, above the upper end of the well or tube S, and its free end is secured to a belaying-cleat, belaying-pin, or to some convenient support. L is a weight formed upon or rigidly attached to the end of an arm, M, which fits into and is pivoted in a recess formed in the bottom of the vessel, in a manner somewhat similar to a pivoted centre-board. The part of the vessel weakened by cutting out the hole for the recess, to receive the weight L and arm M, is strengthened by flanges N, formed upon or firmly attached to said recess, and securely bolted to the bottom timbers of the vessel. O is a rope or chain, the end of which is attached to the weight L, and which passes up through the tube P, passes over a pulley, R, attached to some suitable support above the upper end of the tube P, and its free end is secured to a belaying-cleat, belaying-pin, or in some other convenient manner.

When arranged in any of these ways, the weight may be instantly lowered when necessary, and easily raised again when no longer required.

Having thus described my invention, what I claim as new therein, and desire to secure by Letters Patent, is—

The temporary ballast, when consisting of the weight F, secured to the lower ends of the rods II, and adapted to fit into the metallic socket G, in the keel of the vessel, and operated from the deck, the rods II working in the vertical tube S, of the socket G, as herein set forth, for the purpose specified.

The above specification of my invention signed by me, this 22d day of October, 1867.

JOHN B. STONER.
